UNITED STATES PATENT OFFICE

ALEXANDER M. BURTON, OF LINCOLN PLACE, PENNSYLVANIA

TROUSERS PRESSER

Application filed June 5, 1929. Serial No. 368,487.

This invention relates to a device for pressing trousers without the application of heat.

The object of the invention is to provide a trousers presser which is simple in its construction, easy to operate, and which presses the legs of the trousers throughout their entire width while exerting an increased pressure along the edges of the trousers leg where a crease is to be made.

10 In the drawings Fig. I is a plan view of the trousers presser of the present invention, showing a pair of trousers in position therein; Fig. II is a cross-sectional view taken on the line II—II of Fig. I, and showing the trousers presser on an enlarged scale; and Fig. III is a fragmentary vertical section taken on the line III—III of Fig. I and showing in detail one end of the hinge of the device.

20 In the drawings the reference numerals 1 and 2 designate, respectively, two relatively wide plates of a suitable resilient material, such as tin, aluminum, or such other metal or composition as may possess the requisite strength and resiliency. The hinge structure of the device comprises a rod 3 which extends the entire length of the plates, and which is embraced by a curled portion 4 of the upper resilient plate 1. The curled portion 5 of the lower resilient plate 2 engages the portion 4 of plate 1 in such manner that it is irremovably fixed thereto, but has a sliding contact therewith. At the ends of the plate 1 and rod 3 the portion 4 of the plate is distorted to receive a suitable ferrule 6, of rubber or other suitable material. This ferrule prevents dislodgment of the rod 3 and makes a smooth end to the hinge, so that it will not catch in clothing or other fabric.

25 Along the edge of the plates 1 and 2, lying outside the hinge structure, the plate 1 has a portion 7 arranged to embrace and clinch a rod 8. The lower plate 2 has an extension 9 with a portion 10 curled to embrace and clinch a rod 11.

As shown in Fig. II, the unhinged edge of plate 1 may be raised by springing the portion 9 of the resilient plate 2, and the portion 7 of plate 1 may be forced past the portion 10 of the plate 2, so that the plates are mutu-

ally engaged along their unhinged edges by the resilient engagement of these portions. It should be noted that the plate 2 has longitudinally extending inclined areas 12 adjacent each edge of the plate, to exert a particular pinching effect along the edges of a pair of trousers clamped in the device.

Because of the flatness and resiliency of the presser plates 1 and 2 a pressing effect is exerted across the entire width of the trousers. Because of the fact that the engagement both along the hinged edge of the device and along the opposite edge is continuous, full advantage is taken of the resiliency of the plates, both adjacent these edges and across the entire width of the face. Because of the fact that there is positive engagement between the two plates adjacent their edges, and because of the inclination of the plate 2 in the longitudinal regions 12, there is an emphasized pressing effect along the edges of the trousers to form the desired creases.

What I claim is:

A device comprising a pair of resilient plates of relatively stiff sheet-metal, said plates being mutually hinged along one edge and adapted to receive between them a pair of trousers which are arranged for pressing, each of said plates being provided along the edge thereof which is opposite to its said hinged edge with means for interlocking the plates, one of said plates being deflected along its extent to provide an area which is inclined from the body of the plate toward said hinged edge, and one of said plates being deflected along its extent to provide an area which is inclined from the body of the plate toward its said interlocking means; the above-mentioned characteristics of said sheet-metal being such, and the inclined areas of said plates being so disposed, that in service the two plates assume, with the exception of said inclined areas, substantially a position of parallelism, and exert flattening pressure upon the trousers throughout their width, and exert a pinching effect along the creases of said trousers.

In testimony whereof I have hereunto set my hand.

ALEXANDER M. BURTON. 100
